UNITED STATES PATENT OFFICE

ARTHUR O. DUPUY, OF BEACON, NEW YORK, ASSIGNOR TO NEW YORK BRICK HANDLING CORPORATION, OF NEW YORK, N. Y., A CORPORATION OF NEW YORK

PALLET CONVEYER

Application filed October 29, 1929. Serial No. 403,974.

This invention relates to conveyers and it is directed to the solution of the problem that arises where two or more convergent branches of a conveyer system meet at a single 5 common or trunk conveyer. In such systems the difficulty is ordinarily encountered, that articles placed on the convergent branch conveyers frequently reach the trunk conveyer together with the result that one or 10 both of them are displaced or toppled from the conveyer.

The general object of the present invention is the provision of means for preventing two of the articles or objects being transported by the convergent conveyers reaching the common end of said conveyers at the same time.

Other objects of the invention will appear as the following description of a practical 20 and exemplary embodiment thereof proceeds.

In the drawings, in which the same characters of reference are employed in the several figures to denote identical parts:

Figure 1 is a perspective view of a system 25 embodying the present invention, the construction in this instance being particularly designed for the transportation of bricks in a brick manufactory.

Figure 2 is a perspective view of the same 30 system with the brick carrying pallets omitted in order clearly to disclose the underlying structure.

Figure 3 is a top plan view of the system, somewhat diagrammatically illustrated.

Figure 4 is a fragmentary plan view of the 35 left hand branch conveyer.

Figure 5 is a section taken along the line 5—5 of Figure 4.

Figure 6 is a view similar to Figure 4, but 40 showing the right hand conveyer.

Figure 7 is a section taken along the line 7—7 of Figure 6.

Figure 8 is a section taken along the line 45 8—8 of Figure 7, while Figure 9 is a section taken along the line 9—9 of Figure 7.

Figure 10 is a partial side elevation of the solenoid 7, stop 6 and associated parts.

Figure 11 is a fragmentary view, being a 50 section through the stop showing the en-

gagement with the stop of one of the brick carrying pallets.

Figure 12 is a detail in section, showing one of the rollers carried by the common continuous flight or belt between the two 55 branch conveyers.

Referring now in detail to the several figures and first advertizing to those general figures in which the entire layout of the system is shown, namely, Figures 1, 2 and 3, the 60 numeral 1 represents a common trunk conveyer which is fed by convergent branch conveyers 2 and 3, each leading from the output end of a brick machine. Pallets 4 and 5 are delivered to the branch conveyers either manually or automatically, as the case may be, and are transported by the conveyers to the trunk conveyer, by which last named conveyer they are carried to the point of final disposal.

The pallets 4 and 5 are delivered to the branch conveyers as fast as they can be supplied by the brick machines and in the usual order of events, unless special means is provided to prevent it, pallets on each of the conveyers frequently reach the common ends of the conveyers at the same time, with the result that they displace one another even to the extent of one or both of the pallets with its load of bricks being pushed entirely off of the conveyer.

The present invention, as has been stated above, under the head of general objects, is to provide means for preventing the collision of the pallets when they reach the common 65 end of the conveyer and the said means acts in general by retarding the progress of one of a pair of pallets so positioned upon the respective conveyers that they would collide at the convergent end of said conveyer, so that no 70 two pallets can ever reach the said common end together.

In the exemplary embodiment of the invention as illustrated, the means which have been provided for this purpose are electrical- 75 ly controlled, although it is well within the purview of the invention to provide means which are entirely structurally mechanical without involving in any way the agency of electricity.

In the present preferred embodiment of the invention, a stop 6 is provided for one of the branch conveyers. In the present instance this stop is related to the left hand 5 branch conveyer, as viewed in the drawings. The stop 6 is operated by a solenoid 7, structurally indicated in Figure 10 and diagrammatically shown in Figure 3. The solenoid 7 when energized, projects an armature 8 10 which in turn contacts with a lever 9 fixed to the shaft 11 that carries the stop. In the present instance, the stop appears as a simple arm which when in active position, projects above the plane of the branch conveyer, to 15 present an obstruction to the forward progression of the pallet.

The solenoid 7 is in series with a pair of switches 9 and 10, each consisting of the usual 20 fixed and movable contacts. The movable contact in each of these switches projects above the working level of the respective branch conveyers and is actuated by the passage across it, of a pallet. The switches 9 and 10 are so positioned relative to the 25 respective branch conveyers, as to be simultaneously actuated by pallets so placed upon the respective conveyers that if left alone, they would collide at the common end of the said branch conveyers. Since the switches are in 30 series, it is essential for the operation of the solenoid, that both be closed at the same time. If only one, for instance switch 9, is closed by a pallet 4 passed over it while no pallet 5 is approaching on the other conveyer which 35 would collide with it, then switch 10 will not be closed at the same time as switch 9 and the circuit will remain open so that the stop will remain inactive. But if one of the 40 pallets on the branch conveyer 2 shall be in the position for a potential collision with the pallet 5 which has just closed the switch 10, then the said pallet on the branch conveyer 2 will actuate the switch 9 while the switch 10 remains actuated, thus closing the circuit, 45 energizing the solenoid and raising the stop 6 to its obstructive position. The pallet on the conveyer 2 will therefore be inhibited from moving forward until such time as the circuit shall be opened, which time is determined in such a manner that when the pallet 50 on the branch conveyer 2 is finally released from the stop, the conflicting pallet 5 on the conveyer 3 will have passed beyond the point at which a collision of the two pallets might 55 occur.

The lead which the pallet 5 is permitted to gain over the pallet 4 on the conveyer 2 while held up by the stop, is determined by constructing the switch 10 in such a manner as 60 to cause it to remain activated through a certain duration, the value of this duration depending upon a number of factors, for instance the speed of travel of the branch conveyer or the relative speeds of the branch 65 conveyer in the event that they travel at dif-

ferent rates. In the present instance the switch 10 is constructed in the form of a bar 12, best shown in Figure 7, the surface of which extends slightly above the working face of the conveyer, said bar being resiliently supported in a definite elevated position. When a pallet laden with bricks reaches that region of the conveyer in which the bar 12 is located, the latter will be depressed, against the tension of its spring supports. The bar 75 carries the movable contact 13 of the switch, which when the bar is depressed, makes engagement with the fixed contact 14.

On account of the length of the bar there may be some possibility in that particular 80 type of construction shown in the drawings, of one end of the bar tipping upward when the pallet reaches the opposite end of the bar, causing a separation of the switch contacts at the elevated end. In order to prevent the circuit thus being broken during the normal closed period of the switch, a similar pair of switch contacts 15 and 16 are provided at the opposite end of the bar 12. These contacts are connected in parallel in 85 the circuit as is clearly shown in the diagram in Figure 3, which assures that the circuit shall not be broken through tilting of the bar 12, since at least one pair of contacts is always in engagement, whilesoever any part 90 of the bar 12 remains depressed by a pallet.

The switch 9 is arranged in such proximity to the stop 6 that when the movement of the pallet 4 has been inhibited by the stop, the pallet remains over the switch 9 ensuring 100 that this switch shall remain closed until the pallet has been released by the falling of said stop. Thus, when both the switches 9 and 10 have been actuated, it is assured that the circuit will remain closed until the pallet 5 has transversed the length of the bar 12, at 105 which time, as it has been hereinbefore stated, the pallet 5 has advanced beyond the risk of collision with the pallet 4, when it reaches the common end of the branch conveyers.

The construction of switch 9 is illustrated in Figure 5, the same comprising a roller at the end of a stem 17, said stem being resiliently supported by a spring 18 in an elevated position in which the roller extends slightly 115 above the plane of the working face of the conveyer 2, so that it will be depressed when engaged by a pallet. Figure 5 shows that the switch contacts 19 and 20 are together when the switch is depressed. It is of course 120 to be understood that any form of commercial switch may be substituted for the switch herein shown by way of example, without impairing the novelty of the combination which constitutes the present invention.

One skilled in the art will readily appreciate that when a pallet 4 is held up by the stop 6 while the conveyer 2 is still moving, the succeeding pallet on the conveyer 2 will creep 125 up toward the detained pallet so that a com-

paratively narrow space exists between them, consequently, when the stop is at length released through the opening of the circuit by the passage of the pallet 5 off of the switch 10, the pallet 4, thus released from the stop, begins to advance, but before it has progressed very far the succeeding pallet 4 makes contact with the switch 9. This may happen while the pallet 4 is directly over the stop 6 and it may occur, and frequently does happen in the absence of preventive means that while the pallets 4 are in this position, the succeeding pallet 5 reaches the switch 10 and closes the same, thus actuating the stop 6 while the advance pallet 4 is directly above it. This in actual practice causes a number of disadvantages such as wear of the bottom of the pallet, displacement of the pallet relative to the conveyer and undue wear of the stop mechanism. Under such conditions, the stop 6 is prevented, by the present invention, from acting while the advance pallet 4 is above it, by means of a safety switch 21 shown in Figure 3 and shown in detail in Figure 5. This switch also is actuatable by a pallet and is normally closed when in its inactive position. The switch 21 is placed so close to the stop 6 that when a pallet overlies stop 6, it will also overlie the switch 21, keeping its contacts open and thereby breaking the circuit so that regardless of the fact that a pallet 4 may be in operative position relative to the switch 9, at the same time that a pallet 5 is overlying the switch 10, the circuit 35 remains unenergized and the stop 6 is not actuated. When two of the pallets 4 are in close relation as suggested, that is to say one lying above the stop 6 and safety switch 21, while the other lies above the switch 9, and 40 at the same time a pallet 5 is operating the switch 10, the passage of the advance pallet 4 beyond the safety switch releases the latter and the circuit is energized, all three switches being closed. Therefore, the stop 6 is thus 45 actuated and rises up in front of the succeeding pallet 4, detaining the latter.

It is a matter of expediency, although not being material to the invention, if the two branch conveyers travel at different rates of speed, to have the stop and safety switch associated with the slower moving conveyer, the reason being that in time, when the faster conveyer has gained the distance of one pallet, the slower conveyer has simply failed to 55 deliver a pallet, whereas if the stop were placed in relation to the faster moving conveyer, a time comes when the faster conveyer must deliver two pallets in the space between two pallets on the slower running conveyer.

It is to be understood that while the electrical system as described and illustrated refers to a normally open circuit and to switches which close for energizing the solenoid there is nothing peculiar to the invention to limit it to such an open circuit construction, conse-

quently the claims have been couched in such terms as to include a normally closed as well as normally open electrical system.

It will be observed in Figures 1, 2 and 3 that each of the branch conveyers comprise a pair of continuous traveling members 22 and 23 which may be belts, chains or the like, across which the pallets are rested. It is clear that in such a construction, where the two conveyers converge to a common end, the inner or adjacent traveling members 22, 23 terminate at a greater distance from the end of the trunk conveyer 1 than do the outer or more remote continuous traveling members. In order, therefore, to bridge the distance between the convergent ends of the adjacent traveling members and the end of the trunk conveyer, an independent traveling member 24 is provided, substantially bisecting the angle between the two branch conveyers and serving as a common member for both of the conveyers on to which the adjacent ends of the pallets automatically ride in their progress toward the trunk conveyer. The peculiar position of the traveling member 24 causes the pallets to perform a sliding or transverse motion relative to said traveling member. This necessitates that the surface of said member, which makes contact with the pallets shall be designed to cooperate in response to this sliding motion. For this purpose, the surface of the traveling member 24, which may be a belt or chain, as desired, is furnished with a plurality of rollers 25 which act as forward propelling means for the pallets as well as anti-friction members with respect to these sidewise sliding movements of the pallets. The rollers 25 are mounted upon pins 26 supported horizontally by lugs 27, the latter being suitably secured to the belt or chain by suitable means such for example as by the bolts 29. The lugs are so disposed that the axes of the pins 26 are directed longitudinally of the direction of motion of the traveling member 24, and said pins are preferably coaxial. In order to yield freely to the sliding sidewise movements of the pallets which vary somewhat in their angularity as the conveyers progress, the rollers 25 are constructed with lateral and radial freedom of movement with respect to their bearings 30, as shown in Figure 12 so that said rollers have a slight universal movement with respect to the axes of the pins 26, being thus capable of rotating substantially in the direction of the sliding sidewise movements of the pallets regardless of the angular variations in said movements.

It will be understood that the component of the force with which the rollers propel the pallets forward, that is, in the direction of the trunk conveyer, is positive and unaffected by the lateral and radial lost motion between the rollers and the bearings.

The operation of the invention has been fully described in connection with the vari-

ous structural features, so that it appears to be necessary only to state in conclusion that the pallets may be fed on to the respective branch conveyers without regard to any particular time or spacing relation and that the order in which said pallets will be received on the trunk conveyer is automatically taken care of by the instrumentalities of the invention in manner set forth. It is inevitable that even in the best regulated machinery 10 occurrences sometimes happen that necessitate the interruption of the operation and in the present instance, the automatic operation of the conveyer system is dominated by a manual control represented by the handle 15 30, Figure 2, by means of which the stop 6 may be thrown into active position regardless of the situation of any of the pallets or the operative condition of any of the control 20 mechanism.

Although I have illustrated my invention in connection with a conveyer system adapted particularly to the handling of bricks, yet it is to be understood that the inventive principle 25 may be equally well applied to the transportation of any other desired object or article.

While I have in the above description defined a practical embodiment of the invention, it is to be understood that the details of 30 construction as herein specified are merely by way of example and not to be considered limitative and that the scope of the invention is to be determined by a fair interpretation 35 of the terms and intent of the appended claims.

What I desire to claim as my invention is:

1. In a conveyer system comprising convergent branch conveyers delivering at a common 40 point, means to prevent articles traveling on the branch conveyers reaching the common point at the same time, comprising a stop in one branch for inhibiting the progress of an article along said branch, and complementary means in both branches controlling 45 the operation of said stop, upon the actuation at the same time of both said means by articles on the respective branches, the control means in the branch opposite that having the stop, having a greater controlling 50 duration than the means in the other branch, and article actuated safety means in the branch having the stop for inhibiting the operation of said stop by said complementary 55 control means, when an article is obstructing the normal movement of said stop.

2. In a conveyer system comprising convergent branch conveyers delivering at a common 60 point, means to prevent articles traveling on said branch conveyers reaching the common point at the same time, comprising a stop in one branch for inhibiting the progress of an article along said branch, electrical means for operating said stop, said means being intercalated in a circuit including article

actuated control switches arranged in series, one related to each branch conveyer, and so placed as to be actuated at the same time by articles resting on said branch conveyers in potential positions to collide when they shall have reached the common end of said branches, the switch related to the branch conveyer opposite to said stop being constructed to have a longer duration of operation when actuated than the switch related to the branch having said stop, the latter switch being positioned to be actuated by an article before the article reaches the position of said stop, and a safety switch in said circuit related to the branch having the stop, positioned to be operated by an article on said branch conveyer, when said article is obstructing the normal movement of said stop, for inhibiting the effect on said circuit of the simultaneous actuation of said controlling switches while said article is in stop-obstructing position.

3. In a conveyer system comprising convergent branch conveyers delivering at a common point, means to prevent articles traveling on said branch conveyers reaching the common point at the same time, comprising a stop in one branch for inhibiting the progress of an article along said branch, electrical means for operating said stop, said means being intercalated in a circuit including article-actuated control switches arranged in series, one related to each branch conveyer, and so placed as to be actuated at the same time by articles resting on said branch conveyers in potential positions to collide when they shall have reached the common end of said branches, the switch related to the branch conveyer opposite to said stop being constructed to have a longer duration of operation when actuated than the switch related to the branch having said stop, the latter switch being positioned to be actuated by an article before the article reaches the position of said stop, the duration switch comprising a spring supported bar arranged substantially longitudinally of the branch conveyer, and having the upper face thereof lying approximately in the plane of the working surface of the said branch conveyer, and spaced pairs of switch contacts, the movable contact of each pair being carried by said bar and said pairs of contacts being arranged in parallel relation in said circuit.

4. In a conveyer system, convergent branch conveyers and a trunk conveyer, said branch conveyers comprising spaced continuous traveling members, and coming together adjacent the end of the trunk conveyer, the inner continuous traveling members terminating short of the point where they would intersect, and an additional continuous traveling member bridging the distance between the ends of said inner traveling members and the convergent ends of the outer traveling

members, the working face of said additional traveling member comprising a series of rollers having their axes directed longitudinally of said additional traveling member.

- 5. In a conveyer system, convergent branch conveyers and a trunk conveyer, said branch conveyers comprising spaced continuous traveling members, and coming together adjacent the end of the trunk conveyer, the inner continuous traveling members terminating short of the point where they would intersect, and an additional continuous traveling member bridging the distance between the ends of said inner traveling members and the convergent ends of the outer traveling members, the working face of said additional traveling member comprises a series of rollers having their axes directed longitudinally of said additional traveling member, and being oscillatable relative to their axes.

6. An anti-friction device for conveyers adapted to permit transverse and diagonal movements of an article on said conveyer while at the same time propelling said article, comprising a pin, a support therefor adapted to secure said pin to the flexible flight of the conveyer, axially in the direction of movement of the conveyer, and a roller journaled on said pin, constructed to have a substantial degree of universal movement relative to said pin.

7. In a system comprising converging branch conveyers, the combination of a stop in one branch, projected by a magnet into the path of a moving article; an article actuated switch in the same branch close to the stop; an article actuated switch in the other branch in series with the first switch and the magnet, positioned to prevent articles reaching the point of convergence at the same time.

8. In a system comprising converging branch conveyers, the combination of a stop in one branch, projected by a solenoid into the path of a moving article; a switch in the same branch, close to the stop, having a member adapting it to be closed by a passing article; and a switch in the other branch; in series with the first switch and the solenoid; having an extended member adapting it to be closed by a passing article for a longer time than the first switch.

In testimony whereof I affix my signature.
ARTHUR O. DUPUY.
